UNITED STATES PATENT OFFICE.

EDWARD B. HESS, OF BROOKLYN, NEW YORK, ASSIGNOR TO ROYAL TYPEWRITER COMPANY, INC., OF NEW YORK, N. Y., A CORPORATION OF NEW YORK.

TYPE-WRITING MACHINE.

1,267,769.

Specification of Letters Patent. Patented May 28, 1918.

Application filed July 13, 1917. Serial No. 180,261.

To all whom it may concern:

Be it known that I, EDWARD B. HESS, a citizen of the United States, and a resident of the borough of Brooklyn, in the city of New York, county of Kings, and State of New York, have invented certain new and useful Improvements in Type-Writing Machines, of which the following is a specification.

10 The present invention relates generally to typewriting machines and has more particular reference to a new organization of the printing elements and the margin controlling devices.

15 Margin controlling devices, as such, are, of course, well known in the art and, as heretofore constructed, they may be classified under three heads. In one well known type of margin control, the carriage is in the 20 form of a hollow square or rectangle in which the platen is supported about midway of the machine between the front and rear thereof, the margin rail being located in front of the platen but separated therefrom 25 by a considerable distance. In this type of construction, the margin rail and its stops are mounted on the carriage and travel therewith and a single element for coöperating with the stops on the rail is located on 30 a stationary part of the machine: or, the margin rail and its stops are mounted on a stationary part of the machine and a single stop element is mounted on the movable carriage. This type is generally used on machines of the so-called blind type but even 35 in that type it renders the carriage construction unwieldy; and, when applied to visible typewriting machines, the construction manifestly interferes with full visibility of the 40 parts.

Another form of construction heretofore used in the art is exemplified in what is known as the top strike machine in which the margin stops are carried directly upon 45 the rail or track on which the carriage travels: or, in which the margin rail and its stops are closely adjacent to the rail of the carriage. In both of these cases, the margin rail and stops are located under the 50 platen and in a very inaccessible position.

A third construction of margin controlling device is exemplified in the well known Royal typewriting machine in which the margin rail and stops are located in rear of 55 the platen and beneath the paper table. This

location is advantageous in that it gives full visibility but has certain disadvantages which may be briefly summarized as follows: In order to effect adjustment of the marginal stops, it is necessary for the operator to raise the paper table and, when the desired adjustment has been effected, to replace it. Consequently, the adjustment to which the margin stops has been set is not constantly under the eye of the operator. Furthermore, the location of the margin rail on the carriage in the place indicated necessarily increases the width of the carriage and renders a nice balance of it difficult due to the fact that all of the additional elements are located substantially in rear of the platen which results in an uneven distribution of weight.

The main objects of this invention are to render a margin controlling device visible at all times to the operator without interfering with the full visibility of the printing point, to reduce the weight of the carriage and to facilitate the balancing of the parts of the same.

The main feature of the invention resides in arranging the margin controlling devices adjacent the printing point in such manner that the type bars have unobstructed passage to the platen and without interfering with the full visibility at the printing point, this being accomplished by coördinating said margin controlling devices with the other elements of the machine.

In the preferred form of the invention as herein disclosed, the margin controlling devices consist of two rails adjacent to the printing point, one rail being located on each side thereof so that sufficient space is afforded for travel of the type bars to and from the platen. In the particular form in which the invention is herein clothed, the margin rails are located in front of the platen below a horizontal plane through the axis thereof. Each rail is provided with a stop element projecting rearwardly toward the platen; and the platen is provided at each end with a forwardly extending stop element coöperating with its complementary stop element on the margin rails. In connection with these devices there is utilized indicating scales, conveniently carried by the rails, said scales being distinguished from those now employed in that the highest numeral is at the left hand end of each

scale,—that is, the numbering begins with "0" at the right hand end of the left hand scale and continues up to an appropriate number which may be one-half of the letter space numbers but which will usually not exceed thirty letter spaces. Then the numbering begins again at the right hand end of the right hand rail and continues, up to any desired number such as "80", to the left hand end of the right hand rail. Since these scales are associated with the margin control, it is not necessary that the numbering on the right hand scale shall continue uninterruptedly from the point where the numbering of the left hand scale ceases; and it is, therefore, convenient to omit the numbering from 31 to 49 and to start the numbering of the right hand scale at 50.

In coöordinating these margin rails with the other elements of a machine, such as herein disclosed, said margin rails are conveniently mounted on top of the dust sheds, or other suitable support, and are located a sufficient distance forward of the platen to admit of employment of a central type bar guide at the printing point, a ribbon vibrator, a front card guide, etc. Said margin rails are also located below the normal path of the ribbon to and from the ribbon vibrator.

The two margin rails used are of widely different construction owing to the different functions they perform. The rail on the right hand side of the printing center constitutes, in effect, an actuating device for line lock mechanism and also for the bell ringing device, and therefore must have a movable member controlled by coöperation of the stops on the rail and platen; or, in itself, must be movable to perform these functions. In the present instance, said rail has a rocking motion and the stop elements are so arranged that two rocking movements are imparted to it,—one, a partial rocking movement for operating the bell; and the other, a more complete rocking movement for actuating the line lock mechanism. It is also essential that the stop elements should be so arranged that they will be effective whether the operator is using the lower case types or has shifted the mechanism to manipulate the upper case types. In the present instance, where the invention is embodied in a machine in which the carriage and platen are shifted vertically, one of the stop elements, preferably the one mounted on the carriage, is provided with two superposed cam members spaced a distance apart in a vertical direction, one of said cam members being effective in lower, and the other in upper position of the carriage or platen. The stop elements on the right hand side of the printing center are further so arranged that they admit of unobstructed transverse movement

of the platen to the right without operating the bell and line lock while limiting or determining the transverse travel of the platen to the left. Means are further provided for compensating for attempted case shifting 70 operation when the stop elements are in engagement with each other. This is preferably effected by means of yielding connections between the carriage or platen and the stop element carried thereby.

The margin rail on the left hand side of the printing center is of very rigid construction since it receives the endwise thrust of the carriage and platen when moved by the operator to the initial letter space position. 80 Also, the stop elements on the left hand side of the machine are so arranged that an unobstructed transverse movement of the platen to the left will be permitted while the transverse movement of the platen to the right will be limited in accordance with the adjustment of the elements.

In this case also, the parts are so arranged that the stop elements will be effective with the carriage in its raised or lowered position 90 in response to the operation of the case shifting mechanism.

In addition to the foregoing, the parts are, of course, properly coöordinated with suitable margin release mechanism and carriage and stop releasing mechanisms.

Other features of construction will appear as the specification proceeds.

The invention is embodied in a concrete and preferred form in the accompanying 100 drawings in which:

Figure 1 is a top plan view indicating the construction of the machine, to which the invention is applied, in a more or less diagrammatic form and showing the two margin rails, together with complementary stop elements, and with four of a series of type bars indicated, three being shown in a position of rest and one in printing position between the margin rails and against the 105 platen. In this view the key-board has been omitted.

Fig. 2 is a front elevation of a machine embodying the invention with the dust-shed in section and the ribbon spools removed 115 and with parts broken away and omitted, showing more particularly the center card guide, its scale, the ribbon vibrator, the central type bar guide, and a type bar in printing position, and also showing the relation 120 of these elements to the two margin rails and their stop elements.

Fig. 3 is a top plan view also largely diagrammatic in character with parts omitted and broken away and showing more particularly the relation of the margin rail on the right-hand side of the printing center and its associated elements to the bell ringing and line lock mechanism.

Fig. 4 is a side view of the machine, 130

partly in elevation, partly in section and partly broken away, and with elements omitted to illustrate the relation of the right-hand margin controlling devices to the bell 5 ringing and line lock mechanism and margin release mechanism, the parts being shown in the position they normally occupy, except that one type bar is shown in printing position.

10 Fig. 5 is an enlarged view of some of the parts shown in Fig. 4, indicating more particularly the position the parts occupy when the line lock mechanism is operated by the right-hand margin controlling device, and 15 with the case shifting mechanism in its lower position.

Fig. 6 is a fragmentary view showing the controlling member extending from the right hand margin rail to the line lock mechanism, indicating the position the parts occupy when bell ringing is about to occur.

Fig. 7 is an enlarged detail view of the elements appearing in the upper right-hand corner of Fig. 2 with the case shifting mechanism in the upper position.

Fig. 8 is a view looking in the direction of the arrow 8 of Fig. 7.

Fig. 9 is a detail view, partly in section of the left-hand margin controlling devices.

30 Fig. 10 is a fragmentary plan view, partly in section on the line 10—10 of Fig. 8, of some of the elements shown in Fig. 8.

Fig. 11 is a fragmentary view similar to Fig. 8 but showing the parts in the position 35 they occupy when it is attempted to effect the case shifting from lower to upper case when the stop elements are in engagement.

Fig. 12 is a view similar to Fig. 11 but showing the position occupied by the parts 40 when shifting from upper to lower case during engagement of the stop elements.

Fig. 13 is a sectional view on the line 13—13 of Fig. 12.

Fig. 14 is a detail view on the line 14—14 45 of Fig. 12.

Fig. 15 is a detail view showing a modification of the parts shown in Fig. 9.

Figs. 16 and 17 are detail views of a modified construction of stop elements.

50 Fig. 1 indicates the general framework of the machine in which is mounted the carriage race way 2 supporting the carriage 3 and provided with case shifting mechanism indicated by the member 4 so that the carriage 55 and its support may be raised or lowered in a manner well understood in the art. Mounted in the carriage 3 is a platen 5 of any suitable construction and provided with a suitable line space advancing mechanism 6 in 60 the usual manner. 7 indicates a segment on which are pivotally supported type bars 8 normally occupying a forwardly recumbent position with their free ends resting on a head rest 9 located near the forward 65 end of the machine. 10 indicates the key

levers pivotally supported at 11 in a suitable bearing and connected by means of a vertical link 12 to a front link 13 connected to the rear of a type bar by means of a link 14. To link 14 is secured a bar or link 15, the rear end of which is bent to engage a universal bar 16, link 15 being provided with a spring 17, the rear end of which is connected with an adjustable rocking frame 18 and the front end of which is secured to 75 a member 19 carried by link 14. It will be understood that all the type bars, when actuated, move to a common printing point or center. Adjacent to the common printing point of the machine is a type bar guide 20 80 consisting of two converging members suitably mounted by means of the bracket 21 on a stationary part of the machine. Mounted to move with the carriage race way 2, so as to partake of the case shifting movement 85 imparted thereto, is a ribbon vibrator 22, a front card guide 23 and its scale 24. These elements are also located adjacent to the printing point and are intermediate the type bar guide and the platen. Inclosing 90 the upper part of the machine are the dust sheds 25 carrying the ribbon spools 26.

27 indicates a margin rail located on the left-hand side of the common printing center, and 28 indicates another margin rail located on the right-hand side of the common printing center. These margin rails are conveniently supported, in this instance, on top of the dust sheds 25 in front of a vertical line and below a horizontal line drawn through the axis of the platen; below the normal position occupied by the ribbon vibrator and in front thereof, and also in front of the card guide and its scale. In fact, the margin rails, as here shown, are located in front of a vertical line tangent to the front face of the platen, and below a horizontal line tangent to the underside of the platen. It will also be noted that the margin rails are above the series of type bars, and over and substantially in line with the pivots of said type bars. In this case therefore the dust sheds also constitute supports, in front of and below the platen and above a series of type bars, for the margin rails.

Associated with the right-hand margin rail is a stop element 29 adjustably mounted thereon and a stop element or block 30 mounted on the carriage. Said right-hand margin rail 28 is provided with pivot extensions 31 that project into suitable bushings 32 in a stationary part of the framework so that said margin rail 28 is in effect a rocking member. Extending from the lower side of rail 28 is a dependent controlling member 33 having at its lower end an L-shaped slot 34 consisting of a horizontal portion 35 and a vertical portion 36. A spring 37 attached at one end to the dust shed and at its other end to the controlling member 33 normally 125 115 120 125 130 135 140 145 150 155 160 165 170 175 180 185 190 195 200 205 210 215 220 tends to maintain the right-hand margin rail in the position shown in Figs. 4 and 8. 38 indicates the line lock blade carried by the laterally extending bar 39 and normally 5 out of the plane of the locking surfaces 40 of key levers 10, as shown in Fig. 4, being urged into this position by the spring 41 anchored at one point 42 to the framework and having its other end connected to member 43 of bar 39. 44 indicates a stop to limit the outward movement of said line lock blade. Extending between the member 43 and slot 34 of the controlling member 33 is a connection 45. Mounted on the stud 46 10 on the framework is a bell crank 47 one arm of which is connected by means of link 48 to connection 45. 49 is a margin release rod supported in bearings 50 and normally urged outwardly by means of a spring 51. 52 indicates a bell suitably mounted within the machine on the tie plate 53, and 54 is a gong or hammer for the bell suitably attached to the controlling member 33 as shown. 15

25 The stop member 29 is in the form of a guide or carrying member 55, slidable upon the right-hand margin rail 28, and is provided with a spring pressed pawl 56 adapted to engage in notches 57 of said rail. The 20 particular construction here is that the carrying member 55 is provided with a pivot 58 for receiving ears 59 of pawl 56. 60 indicates the spring that presses against the underside of handle portion 61 and normally urges pawl 56 into engagement with one of the notches or teeth 57 of the rail.

The carrying member 55 of the stop member is provided with two dogs or cam members 62 and 63 projecting inwardly toward 25 the platen and spaced apart laterally as shown. The cam member 62 has a cam surface, at a relatively higher point than that of cam member 63, as shown in dotted lines in Fig. 7. The relation of cams 62 and 63 is such that a member engaging beneath said cam surfaces will tilt or rock rail 28 slightly when engaging 62 but will rock or tilt it considerably when engaging 63. The stop element 30 that is mounted to move with the 30 carriage or platen is provided with two dogs or cam members 64 and 65 superposed one above the other and spaced apart for purposes that will be hereinafter described. The upper dog 65 is in the form of a rearwardly tilting latch pivoted at 65^a and has a straight upper surface 65^b and a tapered under surface 65^c. It is normally held in its forwardly projecting position by the spring 65^d. 64^e and 65^e indicate lateral cam faces 35 on cams 64 and 65 and adapted to act on the cams 62 and 63.

Said stop member 30 is pivotally supported on the vertically extending pin 66, carried by the plate 67, and is provided with 40 lugs 68 that bear against the side of the

plate 67 so that the pivotal movement of member 30 is limited in one direction. A coiled spring 69 surrounds the pin 66 and bears with one end against the inner side of plate 67 and with its other end against member 30 so that said member is normally urged into a position where lugs 68 will abut plate 67. Plate 67 is pivotally supported at 70 on carriage 3 and is normally urged into the position shown in Fig. 8 by means 75 of spring 71 connecting plate 67 and carriage 3. The action of the spring is limited by means of the stop pin 72. As the carriage moves to the left and approaches the end of its stroke as determined by the position of the stop element 29, assuming the carriage to be in lower position so far as case shifting is concerned, cam 65 will engage with its cam face 65^e beneath the cam 62 and will tilt the margin rail slightly on its pivots 31 thereby 80 moving the controlling member 33 from the position shown in Figs. 4 and 8 into the position shown by the full lines in Fig. 6. This will cause the controlling member 33 to exert a pull on connection 45 in opposition 85 to the action of spring 41. The relation of 62 and 65^e is, however, of such character that the movement thus imparted is not sufficient to bring the line lock blade 38 beneath the locking surface 40 of key levers 90 10. This movement of the controlling member 33 is, however, sufficient to bring the hammer or gong 54 a short distance away from bell 52 so that when cam 65 has passed beyond cam 62, the margin rail 28 will no longer be acted upon by the member 65 and 100 spring 37, together with spring 41, will serve to restore the controlling member 33 to its original position thereby causing gong 54 to strike bell 52, thus notifying the operator that the carriage is approaching the end of the line. The carriage now continues 105 its lateral movement to the left and cam surface 65^e now encounters cam 63 thereby imparting a tilting movement of relatively considerable amplitude to the margin rail 28, moving controlling member 33 and pulling connection 45 a sufficient distance to bring the line lock blade 38 beneath the locking surfaces 40 of the key levers. The position 110 that the parts occupy at this time is indicated in Fig. 5. It will be understood that it is now impossible to manipulate the key levers to bring the type bars to the printing point and the carriage has reached the end 115 of its movement as determined by the position of the margin stop 29. If, however, it is desired to release the parts to admit of writing additional matter on the same line, the margin release rod 49 is moved inwardly, 120 its inner end being thus caused to engage bell crank 47 which imparts a lifting movement to link 48 that moves connection 45 out of the vertical portion 36 of slot 34 thereby 125 causing spring 41 to move rod 45 through 130

the horizontal portion 35 of slot 34 and admitting of further manipulation of the key levers. It is evident that, as soon as the key levers are so operated, the carriage thereby moving to the left, cam 65 will disengage cam 63, and the controlling member 33 and margin rail 28 will be restored to their original position by action of spring 37, this movement also causing connection 45 to be seated again in the vertical portion 36 of slot 34. It is also evident that, if margin release rod 49 is operated and the controlling member 33 is permitted to descend during further manipulation of the key levers, gong 54 will strike bell 52 a second time. The carriage can, of course, now be advanced to the left until the stop element 30 comes in contact with the curved portion 73 of the dust shed or until the usual stop elements (not shown) in the rear of the carriage come together. It will be understood that, owing to the vertical hinge 66, the carriage can be moved to the right, past the cam members 63 and 62, without effecting any tilting movement of the margin rail 28 and without operating bell and line lock, but that, owing to lugs 68, the movement of the carriage to the left will be interrupted, as previously described, by the coöperation of the stop elements 29 and 30. The cycle of operations has been described in connection with the upper cam member 65 of the stop element 30. This is the cam that will be in operative position when the carriage and platen are in their lower case position, as indicated, for instance, in Figs. 4 and 5. Should the carriage and platen have been moved, however, into upper case position, as indicated in Figs. 7 and 8, then, it is evident, the cam surface 64° will engage with cams 62 and 63 in precisely the same manner as previously described in connection with 65°. It will be understood that the upper and lower cam members 64 and 65 are necessary when the invention is used in a machine having a vertical case shift. In view of this construction, however, it is necessary to make allowance for possible case shift by the operator when the stop member 30 is in engagement with cam member 62 or 63,—that is, approximately in bell ringing or line lock position. It will be observed, that, should it be attempted, when the parts are in bell ringing position, to shift from lower to upper case, elevation of the carriage will take place but engagement of cam 65 with the underside of cam 62 will cause tilting of the margin rail 28 to such extent that the line lock will be actuated through the controlling member 33 and its connections, so that it will not be possible to bring the type bars to the printing position. Also, that the case shifting movement of the carriage into elevated position will be permitted to its full extent without placing undue stress on the margin rail

by reason of the interposition of the pivotal plate 67 which turns on its pivotal point 70 in opposition to the action of spring 71.

Substantially the same action will occur when the parts are in the line lock position. (See Fig. 11).

Should it be attempted to shift from upper to lower case when in either bell ringing or line lock position, the lowering of the carriage will cause the tilting latch 65 to be displaced inwardly and case shifting will be effected (see Fig. 12). When the parts are in line lock position, the shifting from upper to lower case has the additional function of releasing the line lock mechanism since the rocking rail 28 is immediately restored to its position by the action of spring 37.

The left hand margin rail 27 is provided with vertical teeth or notches, as shown, and is adapted to support an adjustable stop element 74 that coöperates with a stop element 75 on the transversely movable carriage. The stop element 74 consists of a carrying member 76, slidably engaged on the rail 27 and is provided with a stop dog 77 consisting, in effect, of an adjustable screw. 78 indicates a pawl, the point of which enters the notches of the rail 27 and is provided with ears 79 overlying the upper and lower side of the carrying member 76. Formed in said ears 79 are slots 80 into which extends a pin 81 on the carrying member 76, the pawl being normally urged into engagement with the notches on rail 27 by means of coiled spring 82 surrounding pin 81 said spring engaging with one end on a portion of the pawl 78 and with its other end on the carrying member 76. The pawl 78 is further provided with a handle or operating member 83, as shown. When the handle is depressed against the action of spring 82, the point of pawl 78 becomes disengaged from the notches in the margin rail 27 and, simultaneously therewith, the carrying member is moved to the left so that pin 81 occupies a mid-position in slot 80. When the pressure on handle 83 is released, the end of pawl 78 enters the notch in rail 27, the pin 81 meanwhile remaining substantially in its mid-position in slot 80. When thereafter the stop element 75 on the carriage engages the stop dog 77, as the carriage is moved to the right, the carrying member 76, and with it the dog 77, is moved to the right a distance equal, substantially, to one letter space, its position being determined by the engagement of pin 81 with the end of slot 80, as shown more particularly in Fig. 1, thereby bringing the carriage to the right to the extreme limit of which the adjustment of the stops admits. The stop member 75 is slidably mounted in the carriage 3 of the machine, in this instance, by means of slots 84 sliding on pins 85 attached to said carriage. A spring 86, anchored on the frame 3 and

connected with the inner end of member 75, normally urges said stop element 75 into its outermost position in the plane of stop dog 77. When the carriage is moved to the right, it will continue its movement until the stop element 75 encounters stop dog 77; but, when moving the carriage to the left with the stop element 75 in a position between the printing point and the stop dog 77, said stop element will be caused to move rearwardly due to the fact that its outer end is beveled, as indicated at 87, said bevel surface coming in contact with a corresponding bevel surface 88 carried by stop element 74. In case it is desired to move the carriage in either direction without interference, the stop element 75 may be withdrawn by engaging the handle portion 89 and moving the end of said stop element out of the plane of 74.

In Fig. 15 is shown a modification of this construction in which a pivotally mounted hand lever 90 is provided with a roller 91 in its lower end which enters a notch 92 on the stop element 75 so that, by manipulation of hand lever 90, said stop element 75 may be withdrawn from active position.

It will be noted that the left hand margin rail 27 is rigidly mounted on the dust shed 25 and is therefore entirely different in its characteristics from that of the right hand margin rail 28. The reason for this will be apparent when it is understood that the left hand margin control devices must register exactly; and their construction therefore must be of such nature that so-called "banking over" will not occur. This is especially necessary in view of the fact that when the carriage is moved by the line space lever to its initial position, the operator will, at times, retract the carriage with considerable force. It will be observed that, so far as the relation of the stop elements 74 and 75 is concerned, it is immaterial whether or not the carriage is shifted into lower or upper case position. In this respect, therefore, it does not resemble the parts on the right hand side of the machine where the stop element of the carriage is engaged with two members on the margin rail and where provision must be made to admit of the passage of the carriage stop past the first dog of the rail stop.

In Figs. 16 and 17 is shown a modification of the stop elements on the right hand side of the printing center. In this form of the invention, the margin rail 28 is mounted to tilt, by means of pivots 31 as previously described, and the stop element carried by the margin rail 28 takes the following form. 93 indicates a carrying element provided with a spring seated pawl 94 which normally engages in the notches of the margin rail 28. 95, 96 indicate the two stop dogs which are

pivotaly supported on horizontal axes 96 and urged, by spring pressure exerted by 65 springs 97, into an upright position against the stop pins 98 so that when the carriage moves toward the left the stop element 99 will engage said dogs successively in the manner described in connection with the 70 first form of the invention and will successively tilt margin rail 28. When, however, the carriage is moved to the right with the stop element 99 in a position between the dogs 95 and the printing center, it is evident 75 that said dogs will yield when encountered, as indicated in dotted lines, and will admit of the undisturbed passage of the carriage to the right.

A characteristic feature of the invention 80 is the scale indication used in connection with the margin rails. This scale indication may be adjacent to, or, more conveniently, upon the top surface of the margin rails as shown. The scale indication on the left 35 hand rail 27 begins with zero at the right hand end of the rail and is continued up to say the letter space thirty. Similarly, the scale indication on the right hand rail 28 begins with say fifty at the right hand end of 90 the rail and continues say to eighty. The intervening numbers thirty-one to forty-nine may, from a practical point of view, be omitted since the stop elements are only intended as margin stops in the true sense of the 95 word. However, it is evident that by extending each rail outwardly, the extent of margin control can be increased.

The peculiar scale indication described is necessary when the stop elements are arranged as in the present case and where full visibility of the margin scale indication is desired.

In operation, the stop elements 74 and 29 are adjusted to the desired position. The 105 carriage or platen is then moved to the right, its transverse movement in that direction being limited by the left hand stop elements 74 and 75, but is unobstructed by the stop elements 29 and 30 on the right hand side. 110 The manipulation of keys 10 now causes the carriage or platen to travel to the left until the stop elements 29 and 30 on the right hand side limits the movement to the left.

I claim:

1. A visible typewriting machine comprising: printing elements including normally forwardly recumbent type bars and a transversely movable carriage having a platen, said carriage and platen being in 120 rear of said type bars, and visible margin controlling devices adjacent the front of the carriage and platen and above the type bars including means movable with the carriage and platen and extending in front thereof, 125 and means mounted independently of said

carriage and platen adjacent to the front thereof and above the type bars coacting with said first means.

2. A typewriting machine comprising: 5 printing elements including a transversely movable platen and type bars, complementary means one relatively fixed and one transversely movable at the right hand side of the machine positioned to determine the

10 extent of the transverse left hand movement of the platen, complementary means one relatively fixed and one transversely movable at the left hand side of the machine positioned to determine the extent of the 15 transverse right hand movement of said platen, a line lock mechanism, and means for actuating said line lock mechanism from the right hand complementary means.

3. A typewriting machine comprising: 20 printing elements including a transversely movable platen and type bars, complementary means in front of the platen one relatively fixed and one transversely movable at the right hand side of the machine positioned to 25 determine the extent of the transverse left hand movement of the platen, complementary means in front of the platen one relatively fixed and one transversely movable at the left hand side of the machine positioned 30 to determine the extent of the transverse right hand movement of said platen, a bell ringing device, and means for actuating the bell ringing device from the right hand complementary means.

35 4. A typewriting machine comprising: printing elements including a transversely movable platen and type bars, complementary means one relatively fixed and one transversely movable at the right hand side 40 of the machine positioned to determine the extent of the transverse left hand movement of the platen, complementary means one relatively fixed and one transversely movable at the left hand side of the machine positioned 45 to determine the extent of the transverse right hand movement of said platen, a bell ringing device, a line lock mechanism, and means for actuating both the bell ringing device and line lock mechanism 50 from the right hand complementary means.

5. A typewriting machine comprising: printing elements including a transversely movable platen and a series of individually mounted type bars having a common printing center, and a pair of margin rails adjacent the platen, one on each side of the printing center, and spaced to afford, between said rails, unobstructed passage of the type bars of the platen.

60 6. A typewriting machine comprising: printing elements including a transversely movable platen and type bars having a common printing center, a pair of margin rails,

one on each side of the printing center, to afford between said rails unobstructed passage of the type bars to the platen, a stop member carried by each of said rails, complementary stop members on the platen for co-operating with the stop members on the rails, line lock mechanism, and means for actuating said line lock mechanism from the rail on the right hand side of the printing center.

7. A visible typewriting machine comprising: printing elements including normally 75 forwardly recumbent type bars having a common printing center, and a transversely movable carriage having a platen, said carriage and platen in rear of said type bars, a pair of margin rails in front of the platen 80 one on each side of the printing center to afford between said rails unobstructed passage of the type bars to the platen.

8. A visible typewriting machine comprising: printing elements including normally 85 forwardly recumbent type bars having a common printing center, and a transversely movable carriage having a platen, said carriage and platen in rear of said type bars, a pair of margin rails in front of the platen 90 one on each side of the printing center to afford between said rails unobstructed passage of the type bars to the platen, a stop element on each of said rails, complementary stop elements on the platen, line lock 95 mechanism, and means for actuating said line lock mechanism from the rail on the right hand side of the printing center.

9. A typewriting machine comprising: printing elements including a transversely 100 movable platen and type bars having a common printing center, a pair of margin rails in front of the platen one on each side of the printing center to afford between said rails unobstructed passage of the type bars 105 to the platen, indicating scales associated with said margin rails, each of said scales having its lowest designation at the right hand end of the rail with which it is associated, a stop element on each of said rails 110 adjustable in accordance with the scale indications, and complementary stop elements on the platen.

10. A typewriting machine comprising: printing elements including a transversely 115 movable platen and a series of individually mounted type bars having a common printing center, and a pair of margin rails mounted adjacent the platen in front of a vertical line and below a horizontal line drawn 120 through the axis of the platen, one on each side of the printing center, and spaced to afford between said rails, unobstructed passage of the type bars to the platen.

11. A typewriting machine comprising: 125 printing elements including a transversely

movable platen and type bars having a common printing center, a pair of margin rails mounted in front of a vertical line tangent to the front face of the platen and below a horizontal line drawn tangent to the under side of the platen one on each side of the printing center to afford between said rails unobstructed passage of the type bars to the platen.

12. A front strike typewriting machine comprising: printing elements including a transversely movable platen and a series of type bars arranged when in inactive position with their heads toward the front of the machine and having a common printing center, and means intermediate the type bars and platen on both sides of the printing center and between which the type bars pass to the printing center for limiting the transverse movement of the platen in both directions.

13. A front strike typewriting machine comprising: printing elements including a transversely movable platen and a series of type bars arranged when in inactive position with their heads toward the front of the machine and having a common printing center, dust-sheds above the type bars and in front of the platen, and means mounted on the dust-sheds on both sides of the printing center and between which the type bars pass to the printing center for limiting the transverse movement of the platen in both directions.

14. A front strike typewriting machine comprising: printing elements including a transversely movable platen and a series of type bars arranged when in inactive position with their heads toward the front of the machine and having a common printing center, means intermediate the type bars and platen on both sides of the printing center and between which the type bars pass to the printing center for limiting the transverse movement of the platen in both directions, a two part scale associated with said means one part on each side of the printing center, the scale indications on both parts running from right to left.

15. A visible typewriting machine comprising: printing elements including a transversely movable platen and a series of type bars having a common printing center in front of a vertical line drawn through the axis of the platen, and means located at both sides of the printing center and between which the type bars pass to said printing center for limiting the transverse movement of the platen in both directions.

16. A visible typewriting machine comprising: printing elements including a transversely movable platen and a series of type bars having a common printing center in front of a vertical line drawn through

the axis of the platen, a guide for the type bars located in front of said printing center, and a pair of margin rails in front of the platen, one on each side of the type bar guide, between which the type bars pass to the printing center.

17. A visible typewriting machine comprising: printing elements including a transversely movable platen and a series of type bars having a common printing center in front of a vertical line drawn through the axis of the platen, a guide for the type bars located in front of said printing center, a pair of margin rails in front of the platen, one on each side of the type bar guide, between which the type bars pass to the printing center, and complementary members on the rails and platen for limiting the transverse movement of the platen in both directions.

18. In a typewriting machine, a transversely movable platen, a pair of margin rails mounted in the framing, one of which is movable, a stop element carried by each rail, a stop element movable with the platen, for engaging the stop element on the movable rail to actuate same, line lock mechanism operated by the movable rail to arrest the movement of the platen in a left-hand direction, and a stop element also movable with the platen for engaging the stop element on the other rail to arrest the movement of the platen in a right-hand direction.

19. In a typewriting machine, a transversely movable platen, a pair of margin rails mounted in the framing, one of which rocks on a longitudinal axis, a stop element carried by each rail, a stop element movable with the platen for engaging the stop element on the rocking rail to actuate same, line lock mechanism operated by the rocking rail to arrest the movement of the platen in a left-hand direction, and a stop element also movable with the platen for engaging the stop element of the other rail to arrest the movement of the platen in a right-hand direction.

20. In a typewriting machine, a transversely movable platen, a bell ringing mechanism, a line lock mechanism, a pair of margin rails mounted in the frame, one of which is movable, a stop element carried by each rail, a stop element movable with the platen for engaging the stop element on the movable rail to actuate same twice during the left-hand traverse of the carriage, first to actuate the bell ringing mechanism and second to operate the line lock mechanism, and a stop element also movable with the platen for engaging the stop element on the other rail to arrest the movement of the platen in a right-hand direction.

21. In a typewriting machine, a transversely movable platen, a pair of margin

- rails mounted in the framing, one of which rocks on a longitudinal axis, a bell ringing mechanism, a line lock mechanism actuated from said rocking rail, a stop element carried by each rail, a stop element movable with the platen for engaging the stop element on the rocking rail to actuate the same twice during the left-hand traverse of the carriage to operate the bell mechanism and thereafter the line lock mechanism, and a stop element also movable with the platen for engaging the stop element on the other rail to arrest the movement of the platen in a right-hand direction.
22. In a typewriting machine, a transversely movable platen, a pair of margin rails mounted in the framing, one of which rocks on a longitudinal axis, a bell ringing mechanism, a line lock mechanism both actuated from said rocking rail, means movable with the platen for rocking the rail twice during the left-hand traverse of the platen and imparting thereto first a limited rocking movement to actuate the bell mechanism and thereafter a more complete rocking movement to actuate the line lock mechanism, and a stop element also movable with the platen for engaging the other rail to arrest the movement of the platen in a right-hand direction.
23. In a typewriting machine, a transversely movable platen, a pair of margin rails mounted in the framing, one of which is movable, case shifting mechanism for the platen, a stop element carried by each rail, a stop element movable with the platen for engaging the stop element on the movable rail to actuate same when the platen is in either of its case shifting positions, line lock mechanism operated by the movable rail to arrest the movement of the platen in a left-hand direction, and a stop element also movable with the platen for engaging the stop element on the other rail to arrest the movement of the platen in a right-hand direction when the platen is in either of its case shifting positions.
24. In a typewriting machine, a transversely movable platen, a pair of margin rails mounted in the framing, one of which rocks on a longitudinal axis, case shifting means for the platen, a bell ringing mechanism, a line lock mechanism, a stop element carried by each rail, means movable with the platen for engaging the stop element on the rocking rail to impart two rocking movements thereto during the left-hand traverse of the platen, one a limited movement to actuate the bell ringing mechanism and the other a more complete movement to actuate the line lock mechanism, the parts engaging when the platen is in either case shifting position, and a stop element also movable with the platen for engaging the stop element of the other rail to arrest the movement of the platen in a right-hand direction when the platen is in either case shifting position.
25. In a typewriting machine, a transversely movable platen, a pair of margin rails mounted in the framing in front of the platen, a stop element carried by each rail projecting rearwardly toward the platen, a stop element movable with the platen and extending forwardly toward the margin rail for engaging the stop element on one of said rails to arrest the movement of the platen in a left-hand direction, and a stop element also movable with the platen and projecting forwardly therefrom toward the margin rails for engaging the stop element on the other rail to arrest the movement of the platen in a right-hand direction.
26. A typewriting machine comprising: printing elements including a transversely movable platen and type bars, complementary means one relatively fixed and one transversely movable at the right hand side of the machine positioned to determine the extent of the transverse left hand movement of the platen, complementary means one relatively fixed and one transversely movable at the left hand side of the machine positioned to determine the extent of the transverse right hand movement of the platen, an indicating scale associated with said left hand complementary means, the indications of which run from right to left, and an indicating scale associated with said right hand complementary means, the indications of which also run from right to left.
27. A visible typewriting machine comprising: printing elements including normally forwardly recumbent type bars and a transversely movable carriage having a platen, said carriage and platen in rear of said type bars, visible margin controlling devices adjacent the front of the carriage and platen and above the type bars including means movable with the carriage and platen and extending in front thereof, and means mounted independently of said carriage and platen adjacent to the front thereof and above the type bars coacting with said first means, an indicating scale in front of the platen and above the type bars on the left hand side of the machine for determining the extent of the right hand movement of the platen, and an indicating scale in front of the platen and above the type bars on the right hand side of the machine for determining the extent of the left hand movement of the platen.
28. A typewriting machine comprising: printing elements including a platen and type bars having a common printing center, said platen having a transverse movement

with relation to the type bars, a pair of margin rails one on each side of the printing center to afford between said rails unobstructed passage of the type bars to the platen, complementary means, one carried by the right hand margin rail and the other adjacent the right hand end of the platen and transversely movable therewith for determining the extent of the transverse left hand movement of the platen, and complementary means, one carried by the left hand margin rail and the other adjacent the left hand end of the platen and transversely movable therewith for determining the extent of the transverse right hand movement of said platen.

29. A typewriting machine comprising: printing elements including a platen and type bars having a common printing center, said platen having a transverse movement with relation to the type bars, a pair of margin rails one on each side of the printing center to afford between said rails unobstructed passage of the type bars to the platen, complementary means, one carried by the right hand margin rail and the other adjacent the right hand end of the platen and transversely movable therewith for determining the extent of the transverse left hand movement of the platen, complementary means, one carried by the left hand margin rail and the other adjacent the left hand end of the platen and transversely movable therewith for determining the extent of the transverse right hand movement of said platen, a line lock mechanism, and means for actuating said line lock mechanism from the right hand complementary means.

30. A typewriting machine comprising printing elements including a platen and type bars having a common printing center, said platen having a transverse movement with relation to the type bars, a pair of margin rails one on each side of the print-

ing center to afford between said rails unobstructed passage of the type bars to the platen, complementary means, one carried by the right hand margin rail and the other adjacent the right hand end of the platen and transversely movable therewith for determining the extent of the transverse left hand movement of the platen, complementary means, one carried by the left hand margin rail and the other adjacent the left hand end of the platen and transversely movable therewith for determining the extent of the transverse right hand movement of said platen, a bell ringing device, and means for actuating the bell ringing device from the right hand complementary means.

31. A typewriting machine comprising: printing elements including a platen and type bars having a common printing center, said platen having a transverse movement with relation to the type bars, a pair of margin rails one on each side of the printing center to afford between said rails unobstructed passage of the type bars to the platen, complementary means, one carried by the right hand margin rail and the other adjacent the right hand end of the platen and transversely movable therewith for determining the extent of the transverse left hand movement of the platen, complementary means, one carried by the left hand margin rail and the other adjacent the left hand end of the platen and transversely movable therewith for determining the extent of the transverse right hand movement of said platen, a bell ringing device, a line lock mechanism, and means for actuating both the bell ringing device and the line lock mechanism from the right hand complementary means.

Signed at New York City, in the county of New York and State of New York, this 12th day of July, 1917.

EDWARD B. HESS
